UNITED STATES PATENT OFFICE.

HENRY H. GRAHAM, OF DANVILLE, ILLINOIS, ASSIGNOR TO ALLITH-PROUTY COMPANY, OF DANVILLE, ILLINOIS, A CORPORATION OF ILLINOIS.

SPRING BUNG.

Application filed November 8, 1920. Serial No. 422,446.

To all whom it may concern:

Be it known that I, HENRY H. GRAHAM, a citizen of the United States, residing at Danville, in the county of Vermilion and State 5 of Illinois, have invented certain new and useful Improvements in a Spring Bung, of which the following is a specification.

My invention relates to the construction of melting and heating furnaces and is especially adaptable to roof construction for these types of furnaces.

My invention is exemplified in the present instance as applied to bungs for forming roofs of malleable iron melting furnaces 15 and the like.

An object of my invention is to improved means of supporting refractory bricks or material in furnace bungs for successful commercial use.

Another object is to provide a furnace roof constructed of metal and refractory materials in such manner that the refractory materials may be retained under yielding pressure with respect to the metal to compensate for the differences in the rates of 20 expansion and contraction of the materials and at the same time adapted to permit rapid application and removal of the refractory material with respect to the metal.

A further object is the provision of means for yieldingly supporting refractory bricks and the like in furnace bungs whereby ready application and removal of the bricks may be accomplished without desplacement, loss 35 or removal of any of the brick supporting elements.

The present practice of supporting refractory bricks in furnace bungs is objectionable in that the expansion and contraction 40 of the bricks must be watched carefully by a furnace attendant and any contraction compensated for by the attendant tightening the screws on the ends of the bungs. This manner of tightening the screws is objectionable, first, because the actual work 45 is undesirable on account of the heat, and second, because it is very difficult to determine definitely how much or how little the adjusting screw should be tightened to obtain the desired result.

Generally speaking, I carry out my invention by mounting at each end of a bung

pivoted heads, the lower ends of which engage the end bricks in the bung and the upper ends of which cooperate with springs 55 to hold the lower ends of the heads tightly against the bricks at all times irrespective of the amount of contraction or expansion. I also provide means for adjusting the tension of the springs.

The novel features of my invention will be described and shown in the accompanying specification and drawings and particularly pointed out in the appended claims.

In the drawings,

Figure 1 is a top plan view of a furnace bung of well-known type provided with various novel features embodying my invention; and

Figure 2 is an elevation of the bung of 70 Figure 1.

The bung shown in the drawings is made of an inverted T-shaped casting having the usual flat lower portion 5 which is curved in elevation to correspond to the desired 75 curvature of the roof of the furnace and wide enough to serve as a support for the refractory bricks 6. A flange or web 7 extends upwardly centrally of the portion 5. Heads 8 are pivoted by means of lateral extensions 8^a at points intermediate their ends at 9 to the web 7 of the bung. The heads 8 comprise lower portions 8^a which extend laterally and engage the endmost brick in the bung, while the upper portions 8^b of the 80 heads are operatively associated with coil springs 10. The springs 10 are mounted on separated end members seats or bosses 11 and 12, which are relatively movable, the member 11 being pivoted at 13 to a projection 14 of the web 7 of the bung. Each of the members 11 and 12 has a central lug 15 directed 85 towards each other and adapted to extend into the interior of the spring for the purpose of centering the same, and for preventing displacement thereof when not under compression. The member 12 is pivoted on

the bolt or other pivot pin 9 and is engaged on its outer face by the end of an adjusting screw 16 which has a head 17 for engagement by a wrench or other tool, the screw 16 being threaded into the upper end 8^b of the head 8. For mounting the bolt 16 in the head 8 a nut is provided in a suitable re-

cess in the end 8^b of the head. The bolt is then passed through this nut so that when turned by a suitable tool applied to the head 17 of the bolt the head 8 may be rocked 5 about its pivot 9 for the purpose of varying the spring pressure on the bricks 6 in the bung. For providing means to lift and move the bung the web is provided with a series of openings 18 to which a clevice or 10 other member 19 may be attached by bolts 20 so that a crane or other lifting mechanism may be attached for moving the bung.

The operation of the device is as follows:

The refractory bricks 6 having been inserted in crosswise position, as shown in the drawings and in a manner well known, the heads 8 are caused to engage the endmost bricks in the bung, the lower ends 8^a bearing against these bricks. A plate or other protector 21 may be interposed if desired between the heads and the bricks to prevent the latter being damaged by reason of the contact therewith of the heads 8. After the bricks are in position the adjusting screws 25 16 are turned so that the tension of the springs 10 will be such as to permit movement of the heads 8 as the bricks contract and expand and at the same time not so great as to break any of the bricks nor to 30 permit buckling under excessive expansion. I have found that a bung constructed in accordance with my invention will last much longer than a bung constructed in accordance with the present practice, that is, 35 where the heads are kept in contact with the bricks by means of adjusting screws turned from time to time by a furnace attendant. My experience has been that with the present bungs many bricks are lost before they have served their usefulness in 40 roof construction by reason of the fact that the furnace attendant was lax in adjusting the screws to correspond to the contraction or expansion of the refractory bricks.

45 It will be observed that my invention is automatic in operation, the adjusting screw 16 once having been manipulated to properly tension the spring 10. In removing the old bricks and applying new bricks to the bung any means may be employed to move the heads 8 about their pivots 9 so that the bricks may be easily applied to the bungs.

I have shown a bung as constructed of cast metal. However, I do not wish to be limited thereto, as a furnace bung may be made of commercial shapes of metals such as I-beams or T-bars or other shapes bent to correspond with the curvature of the furnace roof. In the event bungs are made 60 of commercial shapes the heads of my invention may be secured thereto in a manner similar to that shown in the drawings.

While I have described more or less precisely the details of construction of my invention, I do not wish to be understood as

limiting myself thereto, as I contemplate changes in form and proportion of parts and the substitution of equivalents as circumstances may suggest or render expedient, without departing from the spirit of 70 my invention.

I claim:

1. A bung construction for furnace roofs including in combination, heads pivoted at each end of the bung, said heads being 75 spaced from the bung ends by lateral extensions which are pivotally connected to the bung, an inner spring seat pivoted to the bung, and an outer spring seat having a double pivotal connection with the bung 80 at the head pivotal connection, a spring supported between said seats, and a bolt threaded into the head for co-operation with the outer spring seat for varying the effectiveness of said spring and transmitting the 85 same to the head for co-operating with bricks supported therein.

2. A spring lever construction for retaining bricks in bungs and the like including in combination, heads pivoted intermediate 90 their ends to said bung, the lower ends of the heads adapted to receive and retain refractory material between them, a pair of spaced bosses supported on the bung at each end thereof, a spring retained by and 95 between the bosses of each pair, and a bolt threaded into the upper end of a head adapted to bear against one of the bosses whereby the resiliency of said spring may be imparted to said bricks through said 100 head and varied according to the position of said bolt within said head.

3. In a device of the class described including in combination, a bung formed of metal having a flange and a web, heads 105 pivoted to the web at the ends of the bung by projections whereby said heads may be maintained in spaced relation to the ends of the bung, spring bosses pivoted to the web near the ends of the same, each boss 110 having a centrally disposed lug thereon, the lugs of the bosses at each end of the bung being arranged in pairs with the lugs of each pair extending towards each other for receiving and retaining a coiled spring 115 thereon, and a bolt passing through a head for co-operation with one of said bosses for varying the effectiveness of the spring with respect to refractory materials retained in the bung.

4. In a furnace roof construction, the combination of a metallic bung, heads connected at an intermediate point in their length in a pivotal manner to the bung and having the lower portions thereof arranged to receive and hold refractory material between them, a bolt passing through the upper end of a head, and a spring co-operating with said bolt for pressing the lower ends of the heads against the bricks, said 120 125 130

spring being supported at each end by separated pivoted seats, the seat farther from the head being pivoted to a portion of the bung web and the seat nearer the head being pivoted to the bung at the pivotal connection of the head, each of said seats having lugs on the active surfaces thereof for pro-

jecting into the ends of the spring for preventing displacement of the same with respect to said seats.

Signed at Danville, Illinois, this 30th day of October, 1920.

HENRY H. GRAHAM.
